CLAIM

The ornamental design for a fluorescent lamp power connector, as shown and described.

DESCRIPTION

FIG. 1 is a perspective view of a fluorescent lamp power connector showing our new design,

FIG. 2 is a top view thereof;

FIG. 3 is a bottom view thereof;

FIG. 4 is a side view thereof, the opposite side view being identical;

FIG. 5 is an end view thereof;

FIG. 6 is an opposing end view thereof; and,

FIG. 7 is a perspective view of the top, female plug and the bottom, male plug in a disassembled state.

The broken line showing of the conductors in Figs 1-4 and 7 is included for the purpose of illustrating environmental structure only and forms no part of the claimed design.--
